UNITED STATES PATENT OFFICE.

ANDREW HOLLINGER, OF CANTON, OHIO.

RAILWAY-CROSSING.

No. 799,734.

Specification of Letters Patent.

Patented Sept. 19, 1905.

Application filed February 16, 1905. Serial No. 245,934.

To all whom it may concern:

Be it known that I, ANDREW HOLLINGER, a citizen of the United States, residing at Canton, in the county of Stark and State of Ohio, 5 have invented a new and useful Railway-Crossing, of which the following is a specification.

This invention relates to railway-crossings, and has for its object to improve such structures particularly for the purpose of obviating frogs and for producing continuous rails in each direction of the crossing, thereby avoiding the pounding of the wheels commonly incident at crossings, which is injurious both to the track and to the wheels.

15 Another object of the invention is to provide novel mechanism for shifting certain of the rail-sections of the crossing and to effect locking of these rail-sections in their opposite positions, so as to prevent displacement thereof 20 by the jarring movements occasioned by a passing train.

With these and other objects in view the present invention consists in the combination and arrangement of parts, as will be herein- 25 after more fully described, shown in the accompanying drawings, and particularly pointed out in the appended claims, it being understood that changes in the form, proportion, size, and minor details may be made within 30 the scope of the claims without departing from the spirit or sacrificing any of the advantages of the invention.

In the accompanying drawings, Figure 1 is a plan view of a railway-crossing embodying 35 the features of the present invention. Fig. 2 is a sectional view on the line 2 2 of Fig. 1. Fig. 3 is a fragmentary sectional view taken horizontally through a pair of adjacent movable rail-sections to show the manner of locking the same.

Like characters of reference designate corresponding parts in each and every figure of the drawings.

To illustrate the construction and operation 45 of the present invention, there have been shown in the accompanying drawings a pair of rails 1 of a track running in one direction and rails 2 of a track crossing the first-mentioned track, and while these two tracks have 50 been shown as intersecting at something other than a right angle it will of course be understood that the angle of intersection of the two tracks is immaterial and in nowise affects the invention. The continuation of each rail be- 55 tween the rails of the other track is the same for all of the rails, and therefore a description

of one set of rail extensions is deemed sufficient.

Beneath the overlapped substantially parallel extensible rail-sections 3 and 4 there is a 60 bed-plate 5, upon which the sections are adapted to slide in an endwise direction, the rail-section 3 being held in place by means of the bed-plate, being cleft transversely and then bent up around the adjacent edge of the base 65 of the rail-sections, as at 6, as best indicated in Fig. 2 of the drawings. It will of course be understood that the overhanging flange portions 6 are formed in the original casting of the bed-plate. The shiftable rail-section 4 70 is longer than the section 3, with a laterally-offset portion 4^a overlapping the rail 3, the latter being scarfed, as at 7, to fit snugly against the inclined portion 8, between the main portion and the offset portion 4^a of the 75 rail-section 4, whereby the scarfed portion of the rail-section 3 is adapted to fit the rail 4 with reasonable snugness, so as to form a continuous rail. At that end of the rail-section 4 which is opposite the offset portion 4^a the 80 bed-plate is bent into an upstanding flange or shoulder 9, bearing against the adjacent edge of the base or rail, whereby the rail may be fitted in a tilted position across the top of the flange 9 or engage beneath the overhanging flange 6, so as to secure the rail to the bed-plate without spikes or other extraneous fastenings. It will here be explained that the flanges 6 and 9 prevent any material lateral play of the rail-section 4, while at the 90 same time the rail is capable of being shifted in an endwise direction. At the offset end portion 4^a of the rail 4 there is an upstanding flange 10, which instead of being parallel with the rail-section is set at an inclination 95 thereto, and the adjacent edge of the base of the rail-section is cut to produce an inclined or cam edge 11, working against the flange 10, whereby the offset end portion 4^a of the rail 4 is shifted laterally when the rail-section 100 is moved in an endwise direction, there being a slight space between the rail-section 3 and the offset portion 4^a when the rail-sections are drawn together to enable the slight lateral movement of the offset end portion 4^a, 105 so as to preserve a tight joint between the scarfed end 7 of the rail-section 3 and the rail-section 4. This lateral movement of the offset end portion 4^a of the rail-section 4 is in reality a swinging movement upon the opposite end of the rail as a center, there being sufficient looseness of said other end of the

rail between the flanges 6 and 9 to permit of the required lateral shifting movements of the offset end of the rail-section.

The mechanism for simultaneously shifting the rail-sections 3 and 4 endwise in opposite directions consists of a rock-shaft 12, mounted transversely beneath the rail-sections 3 and 4 in substantial parallelism with and between the rails of the other track and terminating at one end in a weighted crank-arm 13. This rock-shaft carries two pairs of eccentrics, one of which has been shown at 14 in Fig. 2, there being one pair for each set of shiftable rail-sections with the members of each pair lying at opposite sides of the rail. Each rail is provided with an eccentric box or strap 15, rigidly carried by one side thereof and of inverted substantially U shape, the inner face of the box being provided with a suitable lining 16 to engage the periphery of the eccentric, and there being a cross-bar, preferably a bolt 17, connecting the lower ends of the eccentric-box. By manipulation of the weighted crank-arm 13 the rock-shaft 12 may be rotated in either direction, thereby to turn the eccentrics within the eccentric-boxes, and consequently move the shiftable rail-sections 3 and 4 endwise across the bed-plate, so as to project them into engagement with the main rails of the track, as indicated for the track 2, to produce continuous rails for this track at the crossing and to draw together the shiftable rail-sections, so as to separate their outer ends from the track, as indicated by the shiftable rail-sections of the track 1, and thereby provide the necessary room for the passage of wheel-flanges without interference by the other track. It will of course be understood that the eccentrics for each pair of shiftable rail-sections are reversely disposed in order that the rotation of the rock-bar 12 in one direction may properly move the rail-sections simultaneously in opposite directions.

In addition to shifting the rail-sections it is also proposed to lock the same against accidental movements, and this is accomplished by means of locking mechanism consisting of a rocking cross-head 18, fulcrumed intermediate of its ends, as at 19, upon the bed of the track, there being rods or bolt members 20 pivotally connected to the cross-head at opposite sides of its fulcrum and extending away from the cross-head at substantially right angles thereto, the outer free end of each bolt working in an opening 21 formed through the web of the shiftable rail-section 3 and capable of alternate engagement with separate openings 22 and 23 in the offset portion 4^a of the rail 4. This cross-head is operated by a connecting-rod 24, and the bolt 20 always remains in the opening 21 and has a movement sufficient only to withdraw the bolt from one of the openings in the rail 4, and the endwise movement of the latter being regulated to aline one or the other of the openings 22

and 23 with the opening 21, thereby to insure a positive locking of the rail-sections at their opposite limits, and thus preventing the rail-sections from being jarred out of place by the action of passing trains.

If desired, each track may be provided with derailing means consisting of a pivotal rail-section 25, which is actuated by a rod 26, having an eccentric-strap 27, engaging a cam 28 upon the rock-bar 12 of the other track, the rod or bar being connected at its opposite end to a bell-crank lever 29, which is connected to the pivotal rail-section 25. The connection between the pivotal rail-section 25 and the rock-bar is so arranged that when the track 2 is continuous and the track 1 interrupted the pivotal rail-section 25 will be in its normal position in longitudinal alinement with the rail 2; but when the other track 1 is continuous and the track 2 interrupted the derailing rail-section 25 will be moved laterally inward, so as to be in the path of wheel-flanges, and thereby derail the train before reaching the crossing.

A very important advantage of the present invention resides in the overlapping of the endwise-shiftable rail-sections, so as to brace the rail-section 3 by the offset portion 4^a of the rail-section 4 when the two sections are spread to form a continuous track.

Having fully described the invention, what is claimed is—

1. A railway-crossing including endwise-shiftable rail-sections having beveled meeting portions, one of the sections having a laterally-offset terminal lying at the outer side of the other section and operating as a brace therefor.

2. A railway-crossing having endwise-slidable rail-sections, one of the sections having a scarfed inner end, the other section having a laterally-offset portion overlapping the scarfed section and forming a brace therefor, said other section having an inclined portion between the main portion of the rail and its offset portion with the scarfed terminal of the first-mentioned section working in conjunction with the beveled portion to form a close joint between the sections.

3. A railway-crossing having endwise-slidable rail-sections, one of the sections being scarfed at its inner end, the other section having a laterally-offset portion lying at one side of the scarfed section to constitute a brace therefor, said other section having an inclined portion against which the scarfed terminal of the first-mentioned section works, the offset portion of said other rail-section having a lateral movement to bring the same into engagement with the scarfed section when the sections are spread and to move away from the scarfed section when the sections are drawn together.

4. A railway-crossing including a bed member having an overhanging flange at one side

and an upstanding flange at the other side, and endwise - movable rail - sections having their bases supported upon the bed between the upstanding and overhanging flanges, each 5 rail-section capable of being tilted for engagement and disengagement with respect to the overhanging flange.

5. A railway-crossing comprising a bed member having an overhanging flange at one 10 side and an upstanding flange at the opposite side of the bed-plate and set at an angle to the longitudinal axis thereof, and a pair of overlapped endwise-movable rail - sections mounted upon the bed-plate between the 15 flanges and having a scarfed joint, the rail-section which is next to the inclined flange having an inclined portion working against the inclined flange to shift said section laterally during its endwise movement.

20 6. A railway-crossing having endwise-shiftable rail - sections which are overlapped to form a continuous joint, each section having an eccentric-box, and a rock-shaft having reversely-disposed eccentrics working in the 25 respective eccentric-boxes.

7. A railway-crossing having overlapped endwise-shiftable rail-sections to form a continuous joint, and means to lock the rail-sections at their opposite limits.

30 8. A railway-crossing having endwise-shiftable rail - sections which are overlapped to form a continuous joint, one of the rail-sections having an opening and the other provided with two openings for alternate alignment with the opening of the first-mentioned section, and a locking-bolt working in the opening of said first-mentioned section for alternate engagement with the openings of the other section to interlock the two sections 35 at their opposite limits.

40 9. A railway-crossing having a pair of end-

wise-shiftable rail-sections which are overlapped to form a continuous joint, one of the sections having an opening and the other section having a pair of openings for alternate 45 alignment with the opening of the first-mentioned section, a pivotal cross-head, a locking-bolt loosely connected to the cross-head and working in the single opening of the first-mentioned rail-section and capable of alternate 50 engagement with the openings of the other section to lock the two sections at their opposite limits, and means for swinging the cross-head to actuate the bolt.

10. A railway-crossing having endwise- 55 shiftable rail-sections to form continuations of the rails of each track, each pair of shiftable rail-sections being overlapped to form a continuous joint, and means to lock one set of rail-sections when extended to form a continuous track and to lock the other set of rail-sections when drawn together.

11. A railway-crossing having opposite pairs of endwise-shiftable rail-sections which are overlapped to form continuous joints, an 65 intermediately-fulcrumed cross-head mounted between the two sets of rail-sections, bolts pivotally connected to the cross-head at opposite sides of its fulcrum and extending in opposite directions therefrom with their outer 70 ends working in openings in adjacent rail-sections, the respective other rail-sections being provided with pairs of openings for the alternate reception of the bolts to lock the rail-sections at their opposite limits. 75

In testimony that I claim the foregoing as my own I have hereto affixed my signature in the presence of two witnesses.
